UNITED STATES PATENT OFFICE.

JOHN W. REHLING, OF ALLEGHENY, PENNSYLVANIA.

WRENCH.

No. 806,497.

Specification of Letters Patent.

Patented Dec. 5, 1905.

Application filed March 21, 1905. Serial No. 251,339.

To all whom it may concern:

Be it known that I, JOHN W. REHLING, a citizen of the United States, residing at Allegheny, in the county of Allegheny and State 5 of Pennsylvania, have invented certain new and useful Improvements in Wrenches; and I do declare the following to be a full, clear, and exact description of the invention, such as will enable others skilled in the art to which 10 it appertains to make and use the same, reference being had to the accompanying drawings, and to the figures of reference marked thereon, which form a part of this specification.

This invention relates to an improved 15 wrench; and it consists in the certain details of construction and combination of parts, as will be fully described hereinafter.

In the accompanying drawings, Figure 1 is a side elevation of my improved wrench, the 20 same being constructed and arranged in accordance with my invention. Fig. 2 is a section side elevation of the forward portion of the handle, showing the inner segmental thread and the exterior eccentric groove. Fig. 3 is 25 an end elevation of the same. Fig. 4 is a sectional end elevation taken through the handle of the wrench on the line $\alpha\alpha$ of Fig. 1. Fig. 5 is a side elevation of the sliding or movable jaw of the wrench and a portion of the handle 30 of the same, showing a device for locking the said handle to prevent rotatable movement. Fig. 6 is an end elevation of the same.

To construct a monkey-wrench in accordance with my invention, I provide a bar 3, rectangular in cross-section, and fit the same with 35 a stationary head 1 and a sliding jaw 2 after the manner common in this class of tools. The bar 3 is formed on two of its edges for a portion of its length with threads 4, adapted 40 to engage with sectional threads 6, formed in the forward end of the handle 5 in such a manner that the sliding jaw 2 may be locked at any point by engaging said threads the one with the other or by a quarter-turn of said 45 handle release the said jaw to be moved in either direction. Formed at the forward end of the handle 5 is an eccentric groove 7, which engages with a lug 8, formed integral with the under portion of the movable jaw 2, there- 50 by attaching the two together the one to move

with the other. This eccentric connection above described is for the purpose of making slight adjustment of the jaw 2 by turning the handle 5, causing said jaw to be moved back or forward at will.

To lock the handle 5, if it is desired, a device, such as shown at Figs. 5 and 6, is provided, in which case a serrated portion 10 is formed about the handle at the rear of the groove 7 and a movable strap 11 loosely attached to 60 the jaw 2, the said strap being formed with serrations on the inner sides of its free ends to register with those of the handle and held in position by means of a screw 13, operating in a slot 12 in the strap, whereby said strap 65 may be moved forward and back.

The rear portion of the bar 3 (see Fig. 4) is cylindrical 9 and rests in an annular bore in the rear portion of the handle 5 and forms a 70 guide or bearing for said bar.

Various slight modifications and changes may be made in the details of construction without departing from the spirit of the invention. Therefore I do not wish to confine myself to the exact construction, but wish to 75 claim all such as would come properly within the general scope of the invention.

Having thus described my invention, what I claim, and desire to secure by Letters Patent, is—

1. The herein-described monkey-wrench, comprising the bar 3 having a fixed head 1, a moving jaw 2, said bar being formed with threads 4 on two of its sides, a rotatable handle 5, having inner sectional threads 6, and an 85 external eccentric groove 7, said handle being adjustably connected with the sliding head 2 by an integral lug 8 extending into said groove, as and for the purpose described.

2. The herein-described wrench, comprising the bar 3, the fixed head 1 and movable jaw 2, said bar being formed with threads 4 on two of its sides, a rotatable handle attached to said sliding head by means of a lug 8 operating in an eccentric groove 7 formed in the 95 forward end of said handle, and a sliding locking device to hold the handle and prevent turning, substantially as and for the purpose described.

3. The herein-described wrench, comprising

ing the bar 3, the fixed head 1, and movable jaw 2, said bar being formed with threads 4 on two of its sides, a rotatable handle adjustably attached to said sliding head by means 5 of a lug carried by the head and operating in an eccentric groove formed in the handle, said handle being formed with peripheral serrations near its upper end, and said sliding head

carrying a movable locking member adapted to engage said serrations.

In testimony whereof I affix my signature in presence of two witnesses.

JOHN W. REHLING.
